[57] CLAIM

The ornamental design for a multipurpose freezer tray, as shown and described.

DESCRIPTION

FIG. 1 is a perspective view of a multipurpose freezer tray, showing my new design, the broken line showing of additional trays is for illustrative purposes only, and forms no part of the claimed design;

FIG. 2 shows a top view of my claimed design;

FIG. 3 shows a bottom view of my claimed design;

FIG. 4 shows a side view of my claimed design of which the other side is identical; and,

FIG. 5 shows an end view of my claimed design of which the other end is identical.
